UNITED STATES PATENT OFFICE.

JOHN GREIVES, OF BROOKLYN, NEW YORK.

IMPROVED ROCK-DRILL.

Specification forming part of Letters Patent No. 55,488, dated June 12, 1866.

To all whom it may concern:

Be it known that I, JOHN GREIVES, of the city of Brooklyn, in the county of Kings and State of New York, have invented a new and useful Improvement in Rock-Drills; and I do hereby declare that the following is a full, clear, and exact description of the same, reference being had to the accompanying drawings, making a part of this specification, in which—

Figure 1 is a vertical elevation. Fig. 2 is a transverse section taken in the line *x x* of Fig. 1. Fig. 3 is a plan view of the lower end of the drill.

Similar letters of reference indicate similar parts in all the figures.

This invention relates to that class of drills which are employed for boring Artesian wells and for drilling rocks and similar substances; and it consists in a novel construction of such a drill, whereby, though it is made more effective in its operation than the drills in common use, it can be manufactured by any blacksmith of ordinary skill without special tools, and greater facility is afforded for its sharpening and repair.

To enable those skilled in the art to understand the nature and operation of my invention, I will proceed to describe it with reference to the drawings.

A represents the drill-rod, which may be either solid or tubular, and the lower end of which is made square or rectangular in its cross-section, and terminates in a chisel-like edge, *a*, which forms the central cutter of the drill. Placed longitudinally upon each of the flat sides of the square lower end of the drill-rod, and securely fastened thereto by bolts *m*, *n*, is a section, *b*, made of steel-plate, the lower end of which is made sharp to form the edges of the cutters, of which there are three on each section, the sides or lateral edges *c* of the section being turned out at right angles to the central part, which fits against the flat side of the drill-rod, the lower end or edge of the said central part forming one cutter, and the lower edge of the sides *c*, which are turned out at right angles to the central portion of the section, as just described, constituting the other two. One of these sections *b* being secured to each of the four flat sides of the lower end of the drill-rod, the cutters formed by the central portions of the said sections surround the central cutter, *a*, upon the extremity of the drill-rod, while the cutters formed by the adjacent sides *c* of two sections project outward from the corners thereof at right angles to each other,

as clearly shown in Figs. 2 and 3. The central cutter, *a*, projects downward some little distance below the other cutters. The sides *c* are narrower at the top than at the bottom, but are made thicker in order to secure uniform strength throughout the same, the proper shape being given by simply upsetting the metal, which, in reducing its width, makes it proportionally thicker.

In order to prevent the bolts *m* from being broken or injured by the percussive action upon the sections of each stroke of the drill, a collar, *u*, is placed upon the drill-rod *A* above the sections and forced firmly down upon them in such a way as to brace them against the percussion of the blow or stroke, and thus prevent excessive strain upon the bolts *m*, the collar *u* being secured to the drill-rod by a nut fitted to a screw-thread on the rod *a*, or by any suitable means. This collar *u* is only necessary when a solid drill-rod is used, its place being supplied when a hollow drill-rod is employed by the ordinary flange or collar of such hollow rod.

The drill is operated by the same means and in the same manner as other rock-drills, its cutting-edges, formed as just described, abrading and penetrating the rock to be drilled in the same manner. When it is desired that a greater extent of cutting-edges be caused to act upon the rock or stone, as in drilling through very hard rock, a solid steel block may be fitted into each section *b*, resting upon its central portion between its sides *c*, and held in place by the same bolts that confine the section to the drill-rod. The lower ends of these additional steel blocks are made with diamond-shaped points, which assist the action of the cutters formed upon the drill itself.

By forming the cutters in the manner described they may be readily removed from the drill-rod to be sharpened or repaired, which operation, as well as the construction of the cutters in the first place, may be performed by a blacksmith or other comparatively unskilled worker in wrought-iron.

What I claim as new, and desire to secure by Letters Patent, is—

The drill constructed of a central polygonal rod with cutting-point and angular sectional cutters bolted to the sides of said rod, substantially as herein specified.

JOHN GREIVES.
